Primary Examiner—Selina Sikder*Assistant Examiner*—Thomas J Johannes(74) *Attorney, Agent, or Firm*—Peter Ganjian(57) **CLAIM**

The ornamental design for a solenoid valve control unit, as shown and described.

DESCRIPTION

FIG. 1 is a front view of a solenoid valve control unit showing my new design;

FIG. 2 is a back view thereof;

FIG. 3 is a top view thereof;

FIG. 4 is a bottom view thereof;

FIG. 5 is a left side view thereof;

FIG. 6 is a right side view thereof;

FIG. 7 is a top view thereof showing an alternative condition of the invention;

FIG. 8 is a front view thereof showing environmental detail;

FIG. 9 is a top perspective view thereof; and,

FIG. 10 is a bottom perspective view thereof.

The broken lines illustrated in any of the figures illustrate environmental detail and form no part of the claimed design.
